HEAT EXCHANGER

Olaf Rasmussen, Dayton, Ohio, assignor to General Motors Corporation, Detroit, Mich., a corporation of Delaware

Application December 27, 1943, Serial No. 515,734

1 Claim. (Cl. 210—150.5)

1

This invention relates to heat transfer apparatus and is particularly concerned with a combination heat transfer device and filter.

An object of the invention is to provide a heat transfer device in combination with a filter wherein, due to the peculiar nature of the filtering medium, the effective area of the heat transfer surface is greatly increased.

Another object of the invention is to provide an oil cooler and filter wherein water or other cooling medium may be circulated through a plurality of conduits such as, tubes which are carried by and bonded to a porous metal block through which oil may be passed, whereby the oil is filtered and thereby cleaned of extraneous material and simultaneously cooled.

A further object is to provide a plurality of tubes which may be utilized to carry one fluid and to embed these tubes in a block of porous metal through which another fluid may be passed, whereby the temperatures of the fluids passing through the two conducting mediums tends to become equalized.

Further objects and advantages of the present invention will be apparent from the following description, reference being had to the accompanying drawing wherein preferred embodiments of the present invention are clearly shown.

In the drawing:

Fig. 1 is a sectional view through one embodiment of the invention taken on line 1—1 of Fig. 5.

Fig. 2 is a partial fragmentary end view of the element shown in Fig. 5.

Fig. 3 is a sectional view taken on line 3—3 of Fig. 1.

Fig. 4 is an end view of the device shown in Fig. 5 wherein one of the header connections has been removed to show the filter block and tubular radiator therein and

Fig. 5 is a side view of a complete device.

This invention is particularly adapted to cooling devices wherein simultaneous filtering of the medium to be cooled is desired. One embodiment of the invention is particularly adapted for an oil cooler and filter for use in connection with internal combustion engines. One of such combined coolers and filters is shown in section in Fig. 1. This unit as shown is for illustrative purposes only since it is apparent that many variations and embodiments of the same basic invention may be utilized. The unit consists of a main body portion 20 that includes a plurality of tubes 22 preferably copper, which may have any cross section desired. These

2

tubes, spaced in the desired relation to one another, are held between a pair of spaced headers 24 and 26 to which they are brazed or welded or otherwise hermetically secured. The headers 24 and 26 are spaced by means of two side portions or rails 28 and 30 which assembly forms a frame open at both sides thereof.

The frame, formed by the two side rails 28 and 30 of the headers 24 and 26, together with the attached tubes is then preferably placed on a graphite plate and metal powder is poured around the tubes and into the frame which confines the powder. Sufficient metal powder is used to completely fill the frame and surround all of the tubes and cover the upper most thereof, after which the frame with the metal powder therein is preferably vibrated to settle the powder, whereupon additional powder is added until a completely full frame is obtained. Metal powders such as a mixture of copper and tin powder in portions of 90 parts copper and 10 parts tin or a pre-alloyed copper-tin powder wherein the tin coats the copper in the same proportions may be used. The graphite plate with the filled metal frame thereon is then placed in a sintering furnace where it is heated under non-oxidizing conditions to a temperature above the melting point of tin and below the melting point of copper preferably in the neighborhood of from 1600 to 1925° F. for a period ranging from 15 minutes to an hour. Under these temperature conditions, the tin alloys with the copper and forms a highly porous bronze block which is integrally bonded to the frame and is likewise bonded to the tubes in intimate heat transfer relation thereto. The entire assembly is then cooled under non-oxidizing conditions to form a block of porous metal having a plurality of copper tubes extending therethrough.

To this block, two side plate members 32 and 34 are assembled which have central apertures 36 and 38 in the form of connections which may be threaded for the attachment of pipes or may have tubes clamped thereto if desired. Plate members 40 and 42 may be assembled to the other two sides of the block which members have flanged portions 44 and 46 thereon that hold the members 32 and 34 in position. The members 40 and 42 also have central apertures there through in the form of connections 48 and 50. The assembly is next soldered or welded around and flanges 44 and 46 and along all other open joints to form a hermetically sealed unit to which access can be gained only through the connections 36 and 38 or 48 and 50.

In use, a cooling medium such as water is passed through connection 38 in the direction of arrows and then through the tubes 22 and discharged at the other end of the device through connection 48. The oil or other fluid to be filtered and cooled is passed through connection 38 in a direction of the arrows and is then passed through the filter block of porous metal which surrounds the tubes 22 and passes out of the unit through connection 38. When used with an internal combustion engine, the water connections of the device are preferably connected in series with the radiator thereof for example while the oil pump passes oil through the filter medium. With this device it is an easy matter to maintain the oil at temperatures approaching the temperature of the water system. Likewise, during extremely cold weather it is possible to heat up the oil to the temperature of the coolant used in a cooling system of a car.

The device simultaneously filters the fluid being passed through the filter block and cools the same to a temperature approximating the temperature of the coolant passing through the tubes. Due to the fact, that the filter block is metallurgically bonded to the tubes, intimate contact is obtained which provides excellent conduction between the filter block and the cooling medium.

While the description herein has been limited to an oil filter and cooler, it is apparent that a similar device may be used as a heat exchanger for any desired purpose. Likewise any other metals may be used in the device, for example, the filter block may be made from powdered iron which includes small quantities of copper or phosphorus, in the form of ferro-phosphorus, or the filter block may be made from a copper-nickel mixture, copper-zinc or in fact any combination of metal powders that are desirable to have in the filter block. The sintering temperatures are well-known in the art as are alloy types of powders. The descriptions of various alloy powders will be found in Olt Patent 2,273,589. Combinations of metal powder used to make filtering or metering elements may be noted in Koehring Patent 2,198,702. Both of the foregoing patents are assigned to the assignee of the present invention.

Also the tubes 22 may be of any desired material for example, instead of copper, the tubes may be stainless steel, bronze, brass, Monel metal etc. When different porosities of filtering mediums are desired, the use of varying size metal powder can be utilized. For most purposes 150 to 200 mesh powder yields very satisfactory results.

It is to be understood that the specific embodiment of the invention may be varied in design to meet the required needs of any application wherein simultaneous cooling and filtering is desired, likewise the quantity of porous metal may be regulated so that the surface area in relation to the area of the tubular ducts provides the desired thermal effects in connection with the quantity of fluids being passed through the device.

Likewise the device may be used as a heat transfer medium only, when filtering is not desired. In this case large particle size metal powder is desirable in the fabrication of the porous block, for example 100 mesh whereby the block is highly porous and causes only a relatively small pressure drop in fluids passing therethrough.

While the embodiments of the present invention as herein disclosed, constitute preferred forms, it is to be understood that other forms might be adopted, all coming within the scope of the claim which follows.

30 What is claimed is as follows:

A combination filter and cooling device comprising a block of highly porous bronze made from sintered, substantially non-compacted metal powder, a plurality of copper tubes running through said block and metallurgically bonded thereto, said tubes being embedded in the block prior to said sintering operation whereby bonding and sintering are accomplished simultaneously, a housing for said block including header portions at each end of said block and around the ends of said tubes so that a fluid can be circulated through said tubes, and a second pair of headers associated with said housing for closing the same whereby another fluid can be circulated 45 through said porous metal block.

OLAF RASMUSSEN.
